2,684,101

TUBE-SWAGING AND THREAD-ROLLING APPARATUS

John W. Clerke, Little Falls, N. J.

Application April 28, 1950, Serial No. 158,645

8 Claims. (Cl. 153—2)

1

This invention relates to thread-forming apparatus and more particularly to apparatus for forming rolled threads in an end portion of a section of tubing that may be made of a suitable metal, such as stainless steel or the like.

It is a primary object of the invention to provide an improved tool or apparatus for forming rolled threads in an end portion of a section of tubing.

Another object of the invention is to provide apparatus for successively swaging and forming rolled threads in a tubular member.

The invention has for another object the obtaining of an effective fluid-tight seal between complementary tubular elements having matching threads rolled therein by apparatus constructed in accordance with this invention.

Another object of the invention is to provide an accurate, uniform and smooth rolled thread form having improved characteristics.

Another object of the invention is to provide a portable tool adapted to be readily joined to an end portion of a length of tubing, such as stainless steel, swage such end portion of the tubing, form rolled threads in the swaged tubing, and be subsequently withdrawn from the tubing.

Another object of the invention is to provide an improved mandrel for swaging an end part of a length of tubing.

A further object of the invention is to provide a mandrel peripherally configured so as to cooperate with other devices in the ready formation of rolled threads in tubing.

A still further object of the invention is to provide apparatus of the character indicated that is adapted to perform its intended functions in an effective and trouble-free manner.

To the end that the foregoing objects may be attained, a recommended and preferred form of apparatus constructed in accordance with the invention includes a first unit comprising a body and thread-rolling means carried by the body, and a second unit comprising a feed screw threadedly connected to the body and a mandrel. The mandrel includes a first part or shank coaxial with and threadedly connected to the feed screw, a second or intermediate part that is grooved peripherally for coaction with the thread-rolling means in the formation of rolled threads in the tubing, and a third or pilot part adapted to be initially introduced into the tubing. The mandrel shank is normally keyed to the feed screw to prevent relative movement therebetween.

When the apparatus is intended for use to both

2

portion of the mandrel second part remote from the shank is tapered inwardly in the direction of the pilot part. To facilitate swaging of relatively large diameter and/or thick-walled tubing, there is provided a plurality of swaging balls movable in radial passages formed in the mandrel second part. The position of the swaging balls is controlled through the medium of a central or sizing ball, a rod slidable in the mandrel, and associated devices, as will be explained in the detailed description further along herein.

Relative movement between the first and second units is prevented by a latch means that includes a member or rod carried by and slidable in the body and registering with an opening in the feed screw. This rod is normally urged in the direction of the feed screw by a spring which acts to maintain the rod in engagement with the feed screw. The rod is adapted to be moved in a reverse direction against the action of the spring by an arrangement of devices whereby to effect disengagement between the rod and the feed screw, as desired, and thereby permit relative movement between the body and the feed screw.

In the case of relatively small diameter and thin-walled tubing, the swaging balls and control devices therefor may be omitted. A portion of the second part of the mandrel may be tapered, as indicated above, when the apparatus is to be used for the purpose of both swaging and forming rolled threads in the tubing. If the apparatus is intended for use to form the rolled threads only, it is recommended that the second part of the mandrel be substantially uniform in cross section and of such size as to permit a snug gripping fit with the inner surface of the tubing so as to prevent relative movement between the mandrel and the tubing during the thread-rolling operation.

The enumerated objects, as well as additional objects, together with the advantages of the invention, will be readily understood by persons skilled in the art upon reference to the following detailed description, taken in conjunction with the accompanying drawings that respectively describe and illustrate preferred embodiments of the invention.

In the drawings:
Figure 1 is a view in side elevation of a combined tube-swaging and thread-rolling apparatus constructed in accordance with the invention;

Figure 2 is a top plan view of the apparatus shown in Figure 1;

Figure 3 is an enlarged side elevational view of

a plunger that is adapted to cooperate with other devices in controlling the position of a plurality of tube-swaging balls;

Figure 4 is an enlarged fragmentary view taken along line 4—4 of Figure 2;

Figure 5 is a view in enlargement taken along line 5—5 of Figure 2, and additionally shows the pilot part of the mandrel positioned in an end portion of a section of tubing:

Figure 6 is a view taken along line 6—6 of Figure 5;

Figure 7 is a view taken along line 7—7 of Figure 5;

Figure 8 is a view corresponding to Figure 5, and shows another relative position of the tool of the invention with respect to the section of tubing. In this figure, the parts are shown at the completion of the swaging operation but before the thread-forming operation:

Figure 9 is another view corresponding to Figure 5, and shows the relative position of the parts at the completion of both the swaging and thread-forming operations;

Figure 10 illustrates a modified form of the invention and corresponds generally to Figure 5;

Figure 11 shows the parts in the lower portion of Figure 10 in another relative position, and corresponds generally to Figure 8; and

Figure 12 illustrates the apparatus of Figure 10 in another relative position with respect to a tubing section, and corresponds generally to Figure 9.

Referring now to the drawings, wherein like reference numerals denote corresponding parts throughout the several views, a hollow body 15 is formed with a threaded longitudinal central opening 16 and a merging recess 17 at its upper end. Body 15 is provided at its lower end with a flange 18, and at its upper end with a plurality, preferably three, equi-angularly spaced, radially projecting, tapped bosses 20, 21 and 22.

A feed screw 23 having a head 24 threadedly engages threaded opening 16 in the body. The feed screw is machined to obtain an axial tapped opening 25, a transverse blind bore 26 in head 24, and an opening 27 coaxial with opening 25 and communicating with opening 25 and bore 26.

A third roll assembly or means 30, best shown in Figures 5 and 6, comprises a housing consisting of a pair of relatively inverted members 31 and 32. Member 31 includes a downwardly projecting flange 33, a plurality, preferably three, downwardly projecting tubular extensions 34, and a central opening 35. Member 32 is generally the same in construction as member 31, and includes an upwardly projecting flange 36, a corresponding number of upwardly projecting tubular extensions 37, and a central opening 38. A shaft or trunnion 40 is press-fitted in each extension 34 and corresponding extension 37. Freely rotatable about each shaft 40 is a cylindrical thread roller 41 having integral annular thread-rolling elements 42. The axis of each shaft 40 and, therefore, the axes of corresponding thread rollers 41 and thread-forming elements 42 are inclined with respect to the axis of feed screw 23 so as to cooperate with other devices, to be described further along herein, in the formation of helical threads. The thread-rolling assembly housing is attached to body flange 18 and maintained in the illustrated position through the medium of studs 43 and spacer sleeves 44.

Reference is next had to Figures 5 and 7 for details of construction of a mandrel 45 that

is adapted to swage or expand an end portion of a section of tubing and coact with the thread rollers 41 in the formation of rolled threads in the tube. The mandrel includes a shank or threaded upper part 46 that engages tapped axial opening 25 in the feed screw, a lower or pilot part 47, and an intermediate tube-swaging and thread-forming part 48. Intermediate part 48 is formed with a generally helical ridge 49 that is substantially V-shaped in cross section and that defines the outer extremity of a generally helical groove 49'. The lower portion of intermediate part 48 is tapered downwardly and inwardly and merges with pilot part 47, as best shown in Figure 1.

The mandrel is provided with coaxial longitudinal central openings 50 and 51 that are in axial alignment with openings 25 and 27 when the apparatus is assembled. Slidable in opening 50 and extending at its opposite ends into openings 51 and 27 is a rod 52. The tapered portion of the mandrel is provided with a plurality of spaced radial passages 53, each of which is adapted to accommodate a swaging ball 54, preferably made of a suitable hardened steel. A steel sizing or adjusting ball 55 is movable in mandrel opening 51 and bears against each swaging ball 54. An adjusting screw 56 retains sizing ball 55 within the mandrel and limits downward movement of that ball in opening 51. Screw 56 is maintained in desired adjusted position by a lock nut 57 which bears against the lower extremity of the mandrel.

The apparatus of this invention is adapted to swage and roll a thread in an end portion of a section of tubing 58. The major diameter of pilot part 47 is slightly less than the internal diameter of tubing 58 to permit ready insertion of the same into the tubing. The diameter of the portion of intermediate mandrel part 48 below swaging balls 54 is slightly greater than the internal diameter of the tubing, while the diameter of the intermediate mandrel part above the swaging balls is greater than the internal diameter of the tubing.

Concentric with the mandrel is a sleeve 60 that bears at its upper end against the lower end of feed screw 23 and at its lower end against the upper end of intermediate mandrel part 48. The outer diameter of the sleeve is slightly greater than the maximum diameter of the intermediate mandrel portion but is smaller than the diameter of housing openings 35 and 38.

A screw 61 (Figure 4) has a pin extension 62 which registers with an opening 63 defined by feed screw 23 and mandrel shank 46. Screw 61 serves to key the mandrel to the feed screw and prevent movement of the mandrel with respect to the feed screw during the swaging and thread-rolling operations.

A plunger 65, best shown in Figures 3 and 5, is reciprocable in bore 26. This plunger comprises a body 66 and an integral forward spring guide 67 that forms a shoulder 68 with the body. The body is provided with an upper slot 69 that is adapted to receive a retaining screw 70 that permits axial movement but prevents rotational movement of the body with respect to bore 26. Plunger body 66 has a lower slot 71 and an inclined camming surface 72. A helical compression spring 73 bears against body shoulder 68 and normally and yieldingly urges the plunger toward the right, as viewed in Figure 5.

When plunger 65 is in the relative position shown in Figure 5, the upper extremity of rod

52 bears against the portion of the body 66 to the right of camming surface 72, sizing ball 55 is in protracted position as allowed by adjusting screw 56, and swaging balls 54 are in protracted position in their respective passages. When the plunger is in the position shown in Figure 9, spring 73 will have moved the plunger toward the right to the extent allowed by screw 70 and the upper extremity of rod 52 extends into lower slot 71, permitting swaging balls 54 and sizing ball 55 to be retracted in their respective passages.

Reference is next had to Figures 2, 5 and 9 for an understanding of a combined handle and latch means or mechanism 75 for controlling relative movement between the body and the feed screw and for coaction with earlier described devices for controlling the position of swaging balls 54 and sizing ball 55. This mechanism includes a tubular member 76 externally threaded at one end for connection with a tap in boss 20. A member or rod 77 is rotatable and slideable in tubular member 76 and has a flange 78 that is positioned in a spring compartment 79 formed in boss 20. A helical compression spring 80 is coaxial with rod 77 and bears at its opposite ends against flange 78 and tubular member 76 to normally urge rod 77 toward the left, as viewed in Figure 5. The inner end of rod 77 is movable into and out of registry with feed screw bore 26 and is maintained in registry with the bore by spring 80.

The outer end of rod 77 registers with an opening 81 in a knurled cap 82 and is secured to the cap by a pin 83. The cap is notched, as indicated at 84 (Figure 2), to receive a pin 85 carried by tubular member 76. The cap has a camming surface 86 that defines part of notch 84.

For the purpose of effecting disengagement between rod 77 and feed screw 23, cap 82 is gripped and moved toward the right against the action of spring 80, as viewed in Figure 5. This causes rod 77 to be moved toward the right and withdrawal of the inner end of the rod from bore 26 until the parts are in the relative position shown in Figure 9. When the parts are in the position of Figure 9, body 15 may be moved relative to feed screw 23. Upon movement of rod 77 to the position shown in Figure 9, notch 84 is placed out of registry with pin 85, and by giving cap 82 about a quarter turn about its axis, the open end of the cap will bear against pin 85 and maintain the rod in retracted position.

Bosses 21 and 22 are provided with corresponding handles 87 and 88 which may be solid rods or tubular elements externally threaded at their inner ends for connection with corresponding taps (not shown) in the bosses.

For the purpose of briefly outlining the mode of operation of the above described embodiment of the invention, it is first assumed that the parts are assembled and in the relative position shown in Figure 5 so that the inner end of rod 77 registers with bore 26, thereby locking body 15 to feed screw 23; plunger 65 is at its extreme left position as allowed by screw 70 and against the action of spring 73; rod 52 and sizing ball 55 are at their lowermost positions as allowed by adjusting screw 56; swaging balls 54 are protracted outwardly in their respective passages by sizing ball 55; and mandrel pilot part 47 is in the upper end of tubing section 58, which is held in a vise or the like (not shown). With the parts as illustrated and described, ridge 49

of the lower tapered part of the mandrel grips the inner surface of tubing 58.

The tool is then rotated in a clockwise direction, as viewed in Figure 2, by means of handles 75, 87 and 88, which causes helical ridge 49 to bite into and feed the mandrel into the tubing and swaging balls 54 to expand the upper portion of the tubing until the parts are in the relative position shown in Figure 8, at which time the upper part of the tubing has been expanded and its upper extremity bears against the lower end of sleeve 69, which limits movement of the mandrel in the tubing. This completes the swaging operation.

15 Cap 82 is next moved toward the right and against the action of spring 80, as viewed in Figure 8, and simultaneously given about a quarter or half turn about its axis. This retracts the inner end of rod 77 from bore 26 and places notch 84 out of registry with pin 85. The cap may then be released, and its open end will bear against pin 85, maintaining rod 77 out of engagement with the feed screw against the action of spring 80, as indicated in Figure 9.

20 Retraction of rod 77 from bore 26 permits spring 73 to move plunger 65 toward the right from the position shown in Figure 8 to that shown in Figure 9. This allows swaging balls 54 to move inwardly and sizing ball 55 and rod 52 to move upwardly.

25 The handles are again actuated to impart further clockwise rotation to body 15, as viewed in Figure 2. This causes body 15 to turn and move downwardly with respect to screw 23 and thread rollers 41 to cooperate with groove 49' in the mandrel to roll threads in the swaged portion of tubing 58 (Figure 9).

30 The tool may be readily withdrawn from tubing 58 by rotating body 15 in a reverse direction, 40 which permits the body to move upwardly with respect to the feed screw and then permits the mandrel to be unscrewed from the threads previously rolled in the tubing. Rod 77 is maintained in the position shown in Figure 9 during 45 this operation to prevent entry of its inner end in bore 26 and protraction of swaging balls 54 in their passages.

40 In Figures 10-12, there is shown a modified form of the invention which is the same as the earlier described embodiment with the exception that it contemplates the substitution of a mandrel 90 for mandrel 45. Mandrel 90 comprises a shank or first part 91 coaxial and in threaded engagement with feed screw 23, a cylindrical pilot part 92 that is slightly smaller in cross section than the inner diameter of tubing 58, and an intermediate part 93 formed with a helical ridge 94 and a helical groove 94' corresponding to ridge 49 and groove 49' of mandrel 45. Ridge 94 and groove 94' are preferably elements of a true helix defined in a surface of revolution of a right circular cylinder that is slightly greater in diameter than the inner diameter of tubing 58.

55 60 65 If desired, the lower portion of intermediate mandrel part 93 may be tapered downwardly as in the case of mandrel 45. The mandrel of Figures 10-12 is intended for use with relatively small diameter thin-walled tubing, whether intermediate part 93 is as shown or is tapered for swaging purposes.

70 The operation of the form of the invention shown in Figures 10-12 is generally the same as that described in connection with the embodiment shown in Figures 1-9.

From the foregoing, it is believed that the construction, operation, and advantages of my present invention will be readily comprehended by persons skilled in the art. It is to be clearly understood, however, that various changes in the apparatus set forth above may be made without departing from the scope of the invention, it being intended that all matter contained in the description or shown in the drawings shall be interpreted as illustrative only and not in a limiting sense.

I claim:

1. In apparatus of the character described, a first unit comprising a body and thread-rolling means carried by the body, a second unit comprising a feed screw threadedly connected to the body and a mandrel including a first part or shank connected to the feed screw and a second part adapted to be introduced into an end portion of a section of tubing, said second part being grooved peripherally for coaction with the thread-rolling means in the formation of rolled threads in the tubing, said second part having a plurality of angularly spaced, inwardly extending radial openings, a swaging element 25 movable in each opening and adjustable means controlling inward movement of the swaging elements in their openings, latch means preventing relative movement between the body and the feed screw and coacting with the adjustable 30 means to limit inward movement of the swaging elements in their openings, said latch means comprising a member carried by and movable with respect to the body and releasably engaging the feed screw, and means for actuating the member in a manner to effect disengagement between the member and the feed screw to permit relative movement between the body and the feed screw and for releasing the adjustable means to permit further inward movement of the swag- 40 ing elements in their openings.

2. Apparatus in accordance with claim 1 wherein each swaging element is spherical and the adjustable means includes a ball movable in an axial passage formed in the mandrel.

3. Apparatus in accordance with claim 1 wherein the adjustable means comprises a rod movable in an axial passage formed in the mandrel, a spring-pressed plunger slideable in the feed screw and having one end in engagement with the rod, said plunger being maintained in a predetermined position by the member and being movable to another position in response to disengagement of the member from the feed screw.

4. Apparatus in accordance with claim 3 wherein each swaging element is spherical and the adjustable means further includes a ball movable in an axial passage formed in the mandrel

and bearing against each swaging element and against the end of the rod remote from the plunger.

5. A mandrel of the character indicated comprising a first or shank part and second part coaxial with and constituting a continuation of the first part, said second part having a generally helical peripheral groove formed therein, portions of the second part defining the groove forming a generally helical ridge that is adapted to effect firm gripping engagement with the interior of a length of tubing upon introducing the second part in an end of the tubing and imparting angular movement in one direction and axial movement in a corresponding direction to the mandrel with respect to the tubing, said second part having a plurality of angularly spaced, inwardly extending radial openings, a swaging element movable in each opening, and adjustable means controlling inward movement of each swaging element in the corresponding opening wherein each swaging element is spherical and the adjustable means includes a ball movable in an axial passage formed in the second part.

6. A mandrel of the character indicated comprising a first or shank part and a second part coaxial with and constituting a continuation of the first part, said second part having a generally helical peripheral groove formed therein and axially coextensive therewith, the groove defining surface of the second part being so configured as to form a generally helical ridge, said second part comprising a first portion adjacent the shank part and substantially uniform in cross section area and a second portion merging with the end of the first portion remote from the shank part and tapering inwardly in a direction away from the shank part, said second part having a plurality of angularly spaced, inwardly extending radial openings, a swaging element movable in each opening, and adjustable means controlling inward movement of each swaging element in the corresponding opening.

7. A mandrel in accordance with claim 6 wherein each swaging element is spherical and the adjustable means includes a ball movable in an axial passage formed in the second part.

8. A mandrel in accordance with claim 7 wherein the helical ridge is substantially V-shaped.
